UNITED STATES PATENT OFFICE.

FRANK W. BAKER, OF EAST AURORA, NEW YORK.

WINDMILL.

Application filed July 21, 1926. Serial No. 124,071.

This invention relates to a wind mill, the general object of the invention being to provide means for adjusting the turntable to place the wheel in the wind and to lock 5 the turntable in its adjusted position.

Another object of the invention is to provide means for locking the vane or rudder to the turntable, with the wheel parallel with the vane so that the mill will be inoperative.

A further object of the invention is to provide means for releasing the vane from the turntable by movement of the driven shaft through means located on the base 10 of the mill.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an elevation of the apparatus, with the parts in inoperative position.

Figure 2 is a view taken at right angles to Figure 1.

Figure 3 is a section on line 3—3 of Figure 1.

Figure 4 is a section on line 4—4 of Figure 2.

Figure 5 is a section on line 5—5 of Figure 4.

Figure 6 is a section on line 6—6 of Figure 1.

Figure 7 is a section on line 7—7 of Figure 6.

In these views, 1 indicates the tower which is mounted upon the base 2, and 3 indicates a cap which is connected to the 45 top of the tower. The cap has its top face machined to engage the machined lower face of a turntable 4 so that the turntable can have free rotary movement on the cap. The cap is provided with a depending boss 50 at the center, through which a sleeve 6 passes, said sleeve depending from the table 4, a collar being fastened to the sleeve by a bolt 8 and engaging the lower end of the boss to hold the turntable on the cap. Said 55 table carries the bearings 9 for the horizontal shaft 10 to which the spider 11 of

the wind wheel 12 is fastened. A flanged member 13 is attached to the outer end of the shaft 10 and guy wires 14 extend from the member 13 to the wheel to make the 60 wheel very rigid. This shaft 10 has a beveled gear 15 secured thereto, which is designed to mesh with a similar gear 16 fastened to the end of a vertical shaft 17 which passes through the sleeve 6 and through 65 bearings in the lower part of the apparatus. This shaft 17 is vertically movable through means of an eccentric shaft 18 journaled in a small casing 19 resting on the base 2 and a socket member 20 which receives the lower 70 end of the shaft 17 and is moved vertically by the eccentric shaft through means of the shoe 21 which is arranged between the eccentric shaft and the socket member. A ball bearing 22 is located in the lower end of 75 the socket and forms a thrust bearing for the shaft 17. A weighted arm 23 is connected with the eccentric shaft 18 for rocking the same. These parts are so arranged that when the arm has been moved to its 80 limit of movement to one side of the casing, the parts will be in a position with the shaft 17 in its lowest position and when the arm 23 has been swung over to the other limit of its movement, the parts will be in raised 85 position.

The upper end of the shaft 17 engages a lever 24 which is pivoted intermediate its ends to the turntable and the outer end of said lever is connected by a chain 25 with a 90 weighted latch lever 26 which is pivoted intermediate its ends to an upright 27 formed at one end of a bridge piece 28 which is carried by the turntable and which bridges the shaft 10. This latch lever is 95 designed to lock the vane or rudder 29 to the turntable, the arm 30 of the vane being pivoted to the vertical shaft 31 extending upwardly from the bridge. When the lever 24 is rocked by the upward movement of the 100 shaft 17, it will move the latch lever 26 to releasing position through means of the chain 25. The weight on the end of the latch lever will return the parts to normal position when the shaft 17 is lowered. 105

The turntable is formed with a ring gear 32 with which meshes a pinion 33 which is fastened to the upper end of a vertical shaft 34 having its upper end journaled in a part of the cap and its lower 110 end in a cross piece 35 carried by the tower. The lower part of the shaft 34 has fastened

thereto a gear 36 which meshes with a gear 37 carried by a crank shaft 38 journaled on the cross piece 35, the handle of the shaft being shown at 39. Thus by turning 5 the shaft through means of its handle 39, the shaft 34 will be rotated to rotate the turntable.

The turntable is locked against movement through means of a slide 40 arranged 10 in a guideway 41 formed in the cap and having teeth 42 for engaging some of the teeth of the ring gear 32. A stem 43 is fastened to the slide and a spring 44 on the stem tends to move the slide upwardly to 15 cause its teeth to engage some of the teeth of the ring gear. A chain 45 has one end connected with the stem and its other end connected to a rock shaft 46 which is journaled in journals on the cross piece 35 and 20 this shaft has a weighted arm 47 attached to its outer end for moving the shaft to cause the chain to pull the slide downwardly or to slacken the chain to permit the spring to move the slide upwardly. The movement 25 of the shaft 17 can be transmitted to machinery to be driven through any desired means.

From the foregoing, it will be seen that when the vane is held locked to the turntable by the latch lever, the wheel will be 30 parallel with the vane, as shown in Figures 1 and 2, and if the turntable is free to move, the wind, acting on the vane, will hold the parts with the wheel and vane parallel to the 35 air currents and thus the wheel will not be rotated by the wind. When the device is to be thrown into operation, the lever 23 is swung over so as to lift the shaft 17 and thus move the lever 24 to release the rudder or 40 vane from the latch lever. Then the handle 39 is rotated to rotate the turntable to move the wheel into the wind, after which the lever 47 is swung over to permit the spring to move the slide 40 upwardly and thus lock 45 the turntable in adjusted position. The wheel will then be rotated by the wind so that the shaft 17 will be driven and thus the machinery, which is connected with the shaft, will also be driven. When the device 50 is to be rendered inoperative again, the slide is lowered to unlock the turntable and then the turntable is rotated until the latch lever again engages the rudder, the shaft 17 having first been lowered to permit the latch 55 lever to move into locking position.

It is thought from the foregoing description that the advantages and novel features of my invention will be readily apparent.

I desire it to be understood that I may 60 make changes in the construction and in the combination and arrangement of the several parts, provided that such changes fall within the scope of the appended claims.

What I claim is:—

65 1. A wind mill of the class described

comprising a tower, a driven shaft journaled therein, a turntable rotatably mounted on the top of the tower, a horizontal shaft carried by the turntable, gears connecting the two shafts together, a wind wheel carried by the horizontal shaft, manually operated means for rotating the turntable, locking means for locking the turntable in adjusted position, manually operated means for actuating the locking means, a vane pivotally supported on the turntable, a weighted latch lever on the turntable for holding the vane parallel with the wind wheel, a lever pivoted to the turntable, a flexible member connecting the lever to the latch lever and means for moving the driven shaft vertically to move the lever to a position where the flexible member will move the latch lever to releasing position. 70 75 80

2. A wind mill of the class described comprising a tower, a driven shaft journaled therein, a turntable rotatably mounted on the top of the tower, a horizontal shaft carried by the turntable, gears connecting the two shafts together, a wind wheel carried by the horizontal shaft, manually operated means for rotating the turntable, locking means for locking the turntable in adjusted position, manually operated means for actuating the locking means, a vane pivotally supported on the turntable, a weighted latch lever on the turntable for holding the vane parallel with the wind wheel, a lever pivoted to the turntable, a flexible member connecting the lever to the latch lever, means for moving the driven shaft vertically to move the lever to a position where the flexible member will move the latch lever to releasing position, such means comprising a manually operated cam 95 90 100 105 110 115 120 125 130

3. A wind mill of the class described comprising a tower, a turntable rotatably mounted thereon, a ring gear connected with the turntable, a vertically arranged shaft journaled in the tower, a gear on the upper end of the shaft meshing with the ring gear, manually operated means connected with the lower end of the shaft for rotating the same, a slide arranged on the top of the tower under the turntable and having portions thereon for engaging some of the teeth of the ring gear to lock the turntable against movement and manually operated means for moving the slide out of engagement with the ring gear. 120 125 130

4. A wind mill of the class described comprising a tower, a turntable rotatably mounted thereon, a ring gear connected with the turntable, a vertically arranged shaft jour-

naled in the tower, a gear on the upper end of the shaft meshing with the ring gear, manually operated means connected with the lower end of the shaft for rotating the same, 5 a slide arranged on the top of the tower under the turntable and having portions thereon for engaging some of the teeth of the ring gear to lock the turntable against movement, a spring for normally holding the slide in

engagement with the ring gear, a shaft at 10 the lower part of the tower, a flexible member connecting the shaft with the slide and a weight on the shaft for normally holding the same in a position with the flexible member pulling the slide out of engagement with 15 the ring gear.

In testimony whereof I affix my signature.
FRANK W. BAKER.
